WEIGHT INDICATOR

Seldon Spencer Ridenour, Rock Island, Ill., assignor to
Fairbanks, Morse & Co., Chicago, Ill., a corporation
of Illinois

Application July 9, 1954, Serial No. 31,364

Term of patent 14 years

(Cl. D52—10)

Fig. 1

Fig. 2

Fig. 3

Fig. 1 is an isometric view of a weight indicator embodying my new design;

Fig. 2 is a front view of the weight indicator; and

Fig. 3 is a profile view showing the cross-sectional contour of the weight indicator.

The essential features of the design reside in the portions shown in full lines.

I claim:

The ornamental design for a weight indicator, as shown and described.
